(57) **CLAIM**

The ornamental design for an illuminating book cover, as shown and described.

DESCRIPTION

FIG. 1 is a top perspective view of an illuminating book cover in its open state with an illuminating housing on a top interior side thereof, showing my new design;

FIG. 2 is a top plan view thereof;

FIG. 3 is a bottom plan view thereof;

FIG. 4 is a front elevation view;

FIG. 5 is a rear elevation view thereof;

FIG. 6 is a left view thereof;

FIG. 7 is a right view thereof;

FIG. 8 is another top perspective view of the illuminating book cover from FIG. 1, shown with a notebook inserted into a notebook sleeve of the illuminating book cover;

FIG. 9 is a top perspective view of the illuminating book cover from FIG. 1, shown in a closed orientation;

FIG. 10 is a top perspective view of the illuminating book cover from FIG. 1, shown in an open orientation and with the illuminator housing removed from a track mechanism secured to the top interior side of the illuminating book cover to hold the illuminator housing;

FIG. 11 is another top perspective view of the illuminating book cover illustrated in FIG. 10, shown together with the illuminator housing positioned off to a side, and illustrating a housing release button on a right side of the illuminator housing;

FIG. 12 is a top plan view of the illuminating book cover from FIG. 10, shown in an open orientation;

FIG. 13 is a bottom plan view thereof;

FIG. 14 is a front elevation view thereof;

FIG. 15 is a rear elevation view thereof;

FIG. 16 is a left-side elevation view thereof;

FIG. 17 is a right-side view thereof;

FIG. 18 is a perspective view of the illuminator housing of the illuminating book cover from FIG. 1, with the illuminator housing separate and apart from remaining portions of the illuminating book cover;

FIG. 19 is a top plan view thereof;

FIG. 20 is a bottom plan view thereof;

FIG. 21 is a front elevation view thereof;

FIG. 22 is a rear view thereof;

FIG. 23 is a left side view thereof; and,

FIG. 24 is a right-side view thereof.

The broken line showing of portions of the illuminating book cover is included for the purpose of illustrating environmental structure and forms no part of the claimed design.
